UNITED STATES PATENT OFFICE.

PATRICK J. BYRNES AND BENJAMIN B. OSBURN, OF ROCHESTER, NEW YORK.

METHOD OF MANUFACTURING SHOES.

1,313,065.

Specification of Letters Patent. Patented Aug. 12, 1919.

Application filed January 11, 1919. Serial No. 270,625.

To all whom it may concern:

Be it known that we, PATRICK J. BYRNES and BENJAMIN B. OSBURN, citizens of the United States, residing at Rochester, in the 5 county of Monroe and State of New York, have invented certain new and useful Improvements in Methods of Manufacturing Shoes, of which the following is a specification, reference being had therein to the accompanying drawing.

This invention relates to a novel method of manufacturing shoes, and pertains particularly to the sole used in the above method.

15 The primary object of this invention is to last an upper which has attached thereto a welt on a last without the usual insole and then to remove the lasting tacks and cement a thin sole to the welt, and to subject said 20 thin sole to pressure to form a recess within which the bottom filler can be placed and to attach the outsole by means of stitching passing through the edges of the outsole, insole and welt.

25 In the accompanying drawing—

Figure 1 is a longitudinal sectional view of a shoe made according to our improved process.

Fig. 2 shows the first step in the making 30 of the shoe.

Fig. 3 is the second step in the making of the shoe.

Fig. 4 is the third step in the making of the shoe, and

35 Fig. 5 is the fourth step in the making of the shoe.

In carrying out the improved process an upper is taken and is stitched to a welt 2 at 3. The upper with the welt stitched thereto is next taken and lasted by means of tacks 40 5 to a last 4 which comprises the first step in the process.

The second step of the improvement is to remove the tacks and leave therein three 45 headless tacks 6 to hold the upper and welt to the last, and these headless tacks are adapted to come out with the last when it is pulled out. We thus have a shaped upper with only the welt attached thereto.

50 When the shoe is to be completed, a straight flat sole 7 is cemented to the outer

or bottom face of the welt 2 of the upper which is on the last, and this sole may be termed as the thin outer sole, because it is applied to the outer or bottom face of the 55 welt 2. This thin sole 7 is then pressed inwardly by a suitable mechanism (not here shown) until its center portion 8 rests against the bottom face of the last 4, thus forming a recess 9 with a surrounding wall 60 10. When the pressing inward of the sole 7 has been completed and has become set in its pressed position it completes the third step in carrying out the present improvement.

With the thin sole 7 cemented to the welt and pressed inward to form the recess 9, as described, it is then ready to receive a suitable bottom filler 11, and the filling of this recess with the bottom filler is the fourth 70 65 step of the present improvement.

The final step of this improvement is attaching the outer sole 12 outside of the thin sole 7 to the welt 2, by the usual stitching 13. Of course the heel in children's shoes 75 will be built up by a suitable filler 14, preferably of leather.

From the foregoing description it will be observed that a shoe with the present construction has two soles applied to the outer 80 or bottom face of the welt 2, and the inner one 7 pressed inward to perform the function and to have the appearance of the ordinary inner sole.

This improvement effects economy in labor and material over the ordinary way of constructing shoes with the ordinary inner sole applied in the usual manner.

In the manufacture of the shoe, according to the present invention, the thin sole 7 when cemented to the welt 2 is flat and damp and then pressed inward as shown in Fig. 4, and permitted to dry. After it has dried in this pressed position, the filling 11 is placed in the cavity 4 formed by the depressing of the thin sole 7, and then the outer sole is placed in position and attached as above described.

Having thus described this invention, what is claimed and desired to secure by Letters Patent is:

The improved method of constructing a shoe consisting in lasting an upper having

a welt attached thereto on a last, applying and attaching a thin sole to the outer face of said welt, pressing inward the center of said thin sole to form a recess, placing in 5 said recess a bottom filler, and finally applying an outer sole to the outside of the

thin sole and attaching the welt and both soles together by stitching.

In testimony whereof we hereunto affix our signatures.

PATRICK J. BYRNES.
BENJAMIN B. OSBURN.
